UNITED STATES PATENT OFFICE.

JESSE F. BARNHILL, OF PAMPA, WASHINGTON.

RAIL-JOINT.

No. 837,999.

Specification of Letters Patent.

Patented Dec. 11, 1906.

Application filed August 4, 1906. Serial No. 329,240.

To all whom it may concern:

Be it known that I, JESSE F. BARNHILL, a citizen of the United States, residing at Pampa, in the county of Whitman and State of Washington, have invented certain new and useful Improvements in Rail-Joints, of which the following is a specification, reference being had therein to the accompanying drawings.

10 My invention relates to rail-joints, and more particularly to that class wherein a tongue or tenon is formed upon one end of a rail and adapted to enter a mortise or socket in the end of the adjoining rail, so that the 15 two ends of the rails interlock and coöperate, one of the objects of the invention being to provide a joint which will not yield laterally, vertically, nor longitudinally and which does not require fish-plates and bolts or other 20 means to connect the rails.

A further object of my invention is to provide a rail-joint which will permit of reasonable contraction and expansion when the rails are influenced by heat or cold.

25 Other objects and advantages of the invention, as well as the structural features by means of which they are attained, will be made clear by an examination of the specification, taken in connection with the accompanying drawings, in which the same reference-numerals indicate corresponding portions throughout, and in which—

Figure 1 is a perspective of two rail ends constructed in accordance with my invention and showing the rails in the position they assume when expanded, the ends being brought tight together. Fig. 2 is a longitudinal section showing the position assumed by the rails when contracted, leaving a 40 slight space between the ends. Fig. 3 is a sectional top plan showing the ends of the rails together. Fig. 4 is a view of the end of one of the unlocked rails, and Fig. 5 is a view of the end of the other rail.

45 Referring to the drawings, 1 designates ordinary railway-track rails of a well-known type, with the exception that the sides of the web 2 are slightly inclined, said web being somewhat thicker, as at 3, where it joins the 50 base or tread 4 than where it joins the ball or head 5, as shown at 6. At the interlocking ends of said rails the web is enlarged, as at 7, and the end of one rail is cut to form a mortise or socket 8 to receive a tenon or tongue 9, formed integral with the end of

the other rail. The mortise or socket 8 is made somewhat larger than the tongue 9, so that said tongue is freely movable therein to admit of a reasonable amount of longitudinal contraction or expansion of the rails 60 when influenced by heat or cold. At the inner end of the socket 8 is a tongue 10, adapted to fit in a groove 11, cut in the outer end of the tongue 9. The end of the rail having the socket 8 is divided into an upper extension 12 and a lower extension 13, the upper extension having a recess 14 and the lower extension a recess 15. The upper recess 14 is adapted to receive an extension 16, formed integral with the end of the opposite 70 rail, and the lower recess 15, the inner end wall of which is inclined, as at 17, is adapted to receive an extension 18, formed integral with the end of the opposite rail, the end of said extension 18 conforming in contour to the wall 17, against which it is adapted to rest.

In operation the joint is assembled by engaging the two rail-sections at a slight angle and inserting the tongue or tenon 9 in the 80 socket or mortise 8, which act will also bring the extensions 16 and 18 into the recesses 14 and 15. The rails are then lowered or brought to the position shown in Fig. 1, thus completely interlocking the rails and forming 85 a connection which when the rails are spiked to the cross-ties will not permit of any vertical or lateral displacement by vibration or otherwise and obviates the likelihood of rounding the rails at their joints. 90

From the foregoing explanation, taken in connection with the accompanying drawings, it is thought that the construction, operation, and advantages of my invention will be obvious. 95

Having thus described my said invention, what I claim as new, and desire to secure by Letters Patent of the United States, is—

1. In a rail-joint, the combination, of a rail having a web increasing in thickness 100 from top to bottom, the end of the rail being enlarged and provided with a mortise or groove, with a second rail having a web increasing in thickness from top to bottom, and provided with a tongue and adapted to fit and rest within the mortise or groove in the end of the first-mentioned rail, and means for preventing sidewise displacement of the rails when the tongue is resting within the groove. 105 110

2. In a rail-joint, a railway-rail provided with a longitudinal, transverse mortise or groove dividing the end of the rail into an upper and lower part or extension, and vertical recesses in the extensions, in combination with a second rail having longitudinal extensions formed integral therewith and adapted to fit and rest within the recesses in the first-mentioned rail, and a tongue formed integral with the second rail and conforming to the contour of the groove in the first-mentioned rail, said tongue being adapted to fit and rest within said groove.
3. In a rail-joint, a railway-rail provided with a longitudinal, transverse groove or mortise dividing the end of the rail into two parts or extensions, and longitudinal, vertical recesses in said extensions, in combination

with a second rail having longitudinal extensions formed integral therewith and adapted to fit and rest within the recesses in the first-mentioned rail, and a tongue formed integral with said second-mentioned rail and conforming to the contour of the groove in the first-mentioned rail within which it is adapted to fit and rest, said tongue being provided with a groove adapted to receive a tongue formed on the inner end wall of the groove in said first-mentioned rail.

In testimony whereof I hereunto affix my signature in presence of two witnesses.

JESSE F. BARNHILL.
